CONDENSER MOTOR

Frank J. Lyden, St. Louis, Mo.

Application January 22, 1934, Serial No. 707,724

12 Claims. (Cl. 172—233)

This invention relates to single phase alternating current motors of the condenser type.

It is an object of this invention to provide a condenser motor which gives maximum starting torque for a given condenser capacity by proper selection of the ratio of the effective number of turns in the main phase to the effective number of turns in the auxiliary phase at starting.

A further object is to provide a condenser motor which has good running performance, which has maximum quietness by rearranging the starting ratio of the effective number of turns in the main phase to the effective number of turns in the auxiliary phase for the desired running performance, and at the same time rearranging the condensers used at starting to secure the desired effective condenser capacity at running speed.

A further object is to provide a condenser motor in which the ratio of the effective number of turns in the main phase to the effective number of turns in the auxiliary phase between the starting and running may be changed within a wide range by means of a single pole single throw switch.

A further object is to provide a condenser motor in which automatic switching is obtained with extreme simplicity considering the changes accomplished with this simple type of switch.

A further object is to provide a condenser motor in which the automatic switch may be relay controlled.

A further object is to provide a condenser motor which may be of the double voltage type with no changes in connection of the auxiliary winding, condensers, or control means.

Further objects will appear as the description proceeds.

Embodiments of the invention are shown in the accompanying drawings, in which:—

Figure 1 is a diagrammatic view showing one of the forms of the condenser type motor, such view showing a relay switch.

Figure 2 is a view of a further form of the motor, such view showing a centrifugal switch.

Figures 3, 4, 5, and 6 are schematic views showing a few of the many modifications that may be employed.

Referring to Figure 1, it will be seen that the main phase is indicated by the reference character 1, and that the auxiliary phase, which is displaced approximately 90° from the main phase, is composed of three portions 2, 3, and 4. The portions 3 and 4 may be wound in the well known series-parallel manner, or else the entire auxiliary winding may consist of a tapped winding.

The first end of the auxiliary winding 2 is connected to 20 and the last end of the auxiliary winding 2, which is indicated at 8, is connected to a condenser 13. Part of the auxiliary winding 3 is in series with that portion indicated at 2 and in series with the condenser 12. The leads 6 and 7 are connected to the line. The other side of the condenser 12 is connected to the switch point 10. One side of the condenser 13 is connected to the other switch point 9 and also to 10 one side of the condenser 14. The other side of the condenser 14 is connected to the part 4 of the auxiliary winding. The condenser 15 has one side connected the switch point 10 and the other side to the point 11. The point 11 is connected to the point 21.

Either a relay or a centrifugal switch may be employed to automatically change from a starting to a running condition in any of the several forms of the invention. In Figure 1 a relay is shown and in Figure 2 a centrifugal switch is shown, and in the other figures merely a diagrammatic showing of a switch has been given, although it is to be distinctly understood that either form may be employed with any form of the invention.

In all forms of the invention a squirrel cage rotor 5 will be employed but it is also possible to use a wound rotor.

Returning to Figure 1, it will be seen that the lower end of the section 3 of the auxiliary winding is connected to a condenser 12 and the upper end of the section 4 to a condenser 14. These condensers are preferably relatively large and may be low voltage condensers as they are either in series at starting, as shown in Figure 1, or in series with smaller condensers 13 and 14 during running when the automatic switch has opened.

The relay 17, which has a normally closed contact, is provided with a spring biased armature 16 carrying a contact 19 which connects the points 9 and 10. The relay may be either a current responsive relay and connected in series with the main phase, or may be a voltage responsive relay as shown. Its controlling or energizing coil 18 is connected between suitable points in the auxiliary phase. Any of many different points may be selected. However, as shown in Figure 1, it is connected between the upper end of the section 2, namely, the point 20 and the point 10. It is to be distinctly understood that other points of connection may be selected depending upon the particular characteristics desired.

With a relay connection as shown in Figure 1, the relay will open at a predetermined rotor speed.

proved form of such a modification is shown in Figure 6.

Fundamentally it is the same as Figure 1, with the exception that the condensers in Figure 1 are replaced by condenser transformer units. It is not necessary, however, to use separate cores for all four transformers as transformer 51 and 52 may be wound on the same core and transformer 53 and 54 may be wound on another core, resulting in saving of transformer cost.

The motor shown in Figures 2, 3, and 5 can be made in a similar manner.

Regarding the method of winding of the main phase and auxiliary phase, a tapped winding 15 may be best but is not absolutely required. The two sections of the auxiliary winding, which are to be differently connected at starting than at running, may be wound as tapped windings or 20 in the usual series parallel manner. This latter is even possible in the motor shown in Figure 4 where the lower section is disconnected at running and the upper section 41 would act in a consequent pole manner. The same holds true for 25 the main winding if wound in the usual series parallel way, for double voltage.

It will be seen that a novel form of condenser motor has been provided which has a very high starting torque, which has excellent running performance, which is very quiet, and in which any 30 starting characteristic and any running characteristic desired may be secured by the proper design, as indicated hereinabove, and in which each of these characteristics may be secured without affecting or sacrificing the other characteristic.

It is to be particularly noted that although a large number of turns and a large effective capacity for the auxiliary phase, and a smaller effective number of turns and capacity are provided at starting and during running, respectively, that nevertheless a very simple switching arrangement is employed.

The expression "condenser" as used in the claims is to be interpreted as a condenser or as 45 a condenser unit as disclosed in Figure 6, and if interpreted as disclosed in Figure 6, the expression "condenser terminals" is, of course, to be understood as the terminals of the condenser unit which are connected in the system.

It will be noted that this invention provides a condenser motor in which the auxiliary phase is formed of a plurality of sections and that condenser means are provided which have a plurality of sections. These several sections are so related 50 that in effect a four-arm bridge circuit is formed by part of the sections of the auxiliary phase and the condenser. For example, by reference to Figure 1 it is immediately seen that the section 3 and the condenser 12 form one arm, and the condenser 13 forms another arm. The other two 55 arms of this bridge circuit are formed by the section 4 and the condenser 14 as one arm, and the condenser 15 as the other arm. The automatic switch is a switch which connects to the cross-arms of the bridge. In other words, the switch connects on one side to the point 8, and on the other side to the point 10.

In Figure 2 the bridge circuit is formed of the section 25 and the condenser 27 forming one arm, 70 and the condenser 28 forming another arm. The other two arms are formed by the section 26 and the condenser 29 forming one arm, and the condenser 30 forming another arm. The automatic switch connects across this bridge circuit 75 between the points 31 and 32.

Again, in Figure 3 the four arms of the bridge circuit are formed as follows: The section 41 and the condenser 43 form two of the arms, and the section 42 and the condenser 44 form the other two arms. The switch 38 bridges across this 5 four-arm bridge circuit.

These illustrations of the bridge circuit do not exhaust the invention, as is obvious from the other disclosures, but are given to illustrate plainly how the invention provides a bridge circuit in 10 the auxiliary phase and the condensers associated therewith.

Although the invention has been described in considerable detail, it is to be understood that such description is intended as illustrative rather 15 than limiting, as the invention is to be interpreted as claimed.

I claim:

1. A single phase condenser motor of the class described, having two members constituting a 20 stator and a rotor, a main phase winding for connection to a power line and an auxiliary phase winding on one of said members, said auxiliary phase winding having a plurality of sections, condenser means having a plurality of sections, a 25 four-arm bridge circuit formed by part of the sections of the auxiliary phase and the condenser means, each of two of the arms of the bridge circuit having at least one section of the auxiliary phase, and the other two arms each having condenser means therein, a single pole switch connected to the cross arms of the bridge, said bridge circuit constituting a part of the auxiliary phase and being connected in series with the remainder 30 of the auxiliary phase and in parallel with the 35 main phase, said switch having a closed circuit and an open circuit position, said switch in closed circuit position producing one effect of the turns of the auxiliary phase and a certain effective condenser capacity, and when in open circuit position 40 decreasing the effect of the turns in the auxiliary phase and the effective condenser capacity.

2. A single phase condenser motor of the class described, having two members constituting a 45 stator and a rotor, a main phase winding for connection to a power line and an auxiliary phase winding on one of said members, said auxiliary phase winding having a plurality of sections, condenser means having a plurality of sections, a 50 four-arm bridge circuit formed by part of the sections of the auxiliary phase and the condenser means, each of two of the arms of the bridge circuit having at least one section of the auxiliary phase, and the other two arms each having condenser means therein, a single pole switch 55 connected to the cross arms of the bridge, said bridge circuit constituting a part of the auxiliary phase and being connected in series with the remainder of the auxiliary phase and in parallel with the main phase, said switch having a closed circuit and an open circuit position, said switch in closed circuit position producing one effect of the turns of the auxiliary phase and a certain effective condenser capacity, and when in open circuit position 60 decreasing the effect of the turns in the auxiliary phase and the effective condenser capacity, said switch being automatic and opening when the rotor approximates a predetermined speed.

3. A single phase condenser motor of the class described, having two members constituting a stator and a rotor, a main phase winding for connection to a power line and an auxiliary phase winding on one of said members, said auxiliary 75

- phase winding having a plurality of sections, condenser means having a plurality of sections, a four-arm bridge circuit formed by part of the sections of the auxiliary phase and the condenser means, each of two of the arms of the bridge circuit having at least one section of the auxiliary phase, and the other two arms each having condenser means therein, a single pole switch connected to the cross arms of said bridge for producing one effect of the turns in the auxiliary phase when the switch occupies closed circuit position and for reducing the effect of the turns in the auxiliary phase when the switch occupies open circuit position.
4. A single phase condenser motor of the class described, having two members constituting a stator and a rotor, a main phase winding for connection to a power line and an auxiliary phase winding on one of said members, said auxiliary phase winding having a plurality of sections, condenser means having a plurality of sections, a four-arm bridge circuit formed by part of the sections of the auxiliary phase and the condenser means, each of two of the arms of the bridge circuit having at least one section of the auxiliary phase, and the other two arms each having condenser means therein, a single pole switch connected to the cross arms of the bridge, said bridge circuit constituting a part of the auxiliary phase and being connected in series with the remainder of the auxiliary phase and in parallel with the main phase, said switch having a closed circuit and an open circuit position, said switch in closed circuit position producing one effect of the turns of the auxiliary phase and a certain effective condenser capacity, and when in open circuit position decreasing the effect of the turns in the auxiliary phase and the effective condenser capacity, the sections of the auxiliary phase winding forming the bridge circuit having the same number of turns.
5. A single phase condenser motor of the class described, having two members constituting a stator and a rotor, a main phase winding for connection to a power line, and an auxiliary phase winding on one of said members, said auxiliary phase winding having a plurality of sections, condenser means having a plurality of sections, a four-arm bridge circuit formed by part of the sections of the auxiliary phase and the condenser means, each of two of the arms of the bridge circuit having at least one section of the auxiliary phase, and the other two arms each having condenser means therein, a single pole switch connected to the cross arms of the bridge, said bridge circuit constituting a part of the auxiliary phase and being connected in series with the remainder of the auxiliary phase and in parallel with the main phase, said switch having a closed circuit and an open circuit position, said switch in closed circuit position producing one effect of the turns of the auxiliary phase and a certain effective condenser capacity, and when in open circuit position decreasing the effect of the turns in the auxiliary phase and the effective condenser capacity, and a condenser in series with each section of the auxiliary phase forming one arm of the bridge circuit.
6. A single phase condenser motor of the class described, having two members constituting a stator and a rotor, a main phase winding for connection to a power line and an auxiliary phase winding on one of said members, said auxiliary phase winding having a plurality of sections, condenser means having a plurality of sections, a four-arm bridge circuit formed by part of the sections of the auxiliary phase and the condenser means, each of two of the arms of the bridge circuit having at least one section of the auxiliary phase, and the other two arms each having condenser means therein, a single pole switch connected to the cross arms of the bridge, said bridge circuit constituting a part of the auxiliary phase and being connected in series with the remainder of the auxiliary phase and in parallel with the main phase, said switch having a closed circuit and an open circuit position, said switch in closed circuit position producing one effect of the turns of the auxiliary phase and a certain effective condenser capacity, and when in open circuit position decreasing the effect of the turns in the auxiliary phase and the effective condenser capacity, and a condenser forming no portion of the bridge circuit and connected in series with the bridge circuit.
7. A single phase condenser motor of the class described, having two members constituting a stator and a rotor, a main phase winding for connection to a power line and an auxiliary phase winding on one of said members, said auxiliary phase winding having a plurality of sections, condenser means having a plurality of sections, a four-arm bridge circuit formed by part of the sections of the auxiliary phase and the condenser means, each of two of the arms of the bridge circuit having at least one section of the auxiliary phase, and the other two arms each having condenser means therein, a single pole switch connected to the cross arms of the bridge, said bridge circuit constituting a part of the auxiliary phase and being connected in series with the remainder of the auxiliary phase and in parallel with the main phase, said switch having a closed circuit and an open circuit position, said switch in closed circuit position producing one effect of the turns of the auxiliary phase and a certain effective condenser capacity, and when in open circuit position decreasing the effect of the turns in the auxiliary phase and the effective condenser capacity, the capacity of certain of said condensers having different values.
8. A single phase condenser motor of the class described, having two members constituting a stator and a rotor, a main phase winding for connection to a power line and an auxiliary phase winding on one of said members, said auxiliary phase winding having a plurality of sections, condenser means having a plurality of sections, a four-arm bridge circuit formed by part of the sections of the auxiliary phase and the condenser means, each of two of the arms of the bridge circuit having at least one section of the auxiliary phase, and the other two arms each having condenser means therein, a single pole switch connected to the cross arms of the bridge, said bridge circuit constituting a part of the auxiliary phase and being connected in series with the remainder of the auxiliary phase and in parallel with the main phase, said switch having a closed circuit and an open circuit position, said switch in closed circuit position producing one effect of the turns of the auxiliary phase and a certain effective condenser capacity, and when in open circuit position decreasing the effect of the turns in the auxiliary phase and the effective condenser capacity, and a condenser in series with each section of the auxiliary phase forming one arm of the bridge circuit.
9. A single phase condenser motor of the class described, having two members constituting a

- stator and a rotor, a main phase winding for connection to a power line and an auxiliary phase winding on one of said members, said auxiliary phase winding having a plurality of sections, condenser means having a plurality of sections, a four-arm bridge circuit formed by part of the sections of the auxiliary phase and the condenser means, each of two of the arms of the bridge circuit having at least one section of the auxiliary phase, and the other two arms each having condenser means therein, a single pole switch connected to the cross arms of the bridge, said bridge circuit constituting a part of the auxiliary phase and being connected in series with the remainder 10 of the auxiliary phase and in parallel with the main phase, said switch having a closed circuit and an open circuit position, said switch in closed circuit position producing one effect of the turns of the auxiliary phase and a certain effective condenser capacity, and when in open circuit position decreasing the effect of the turns in the auxiliary phase and the effective condenser capacity, said condenser means including step-up transformers and condensers connected to the high tension side 20 of said transformers.
10. A single phase condenser motor of the class described, having two members constituting a stator and a rotor, a main phase winding for connection to a power line and an auxiliary phase winding on one of said members, said auxiliary phase winding having a plurality of sections, condenser means having a plurality of sections, a four-arm bridge circuit formed by part of the sections of the auxiliary phase and the condenser means, each of two of the arms of the bridge circuit having at least one section of the auxiliary phase, and the other two arms each having condenser means therein, a single pole switch connected to the cross arms of the bridge, said bridge circuit constituting a part of the auxiliary phase and being connected in series with the remainder of the auxiliary phase and in parallel with the main phase, said switch having a closed circuit and an open circuit position, said switch in one position producing one effect of the turns of the auxiliary phase and a certain effective condenser capacity, and when in the other position decreasing the effect of the turns in the auxiliary phase and the effective condenser capacity. 25
11. A single phase condenser motor of the class described, having two members constituting a stator and a rotor, a main phase winding for connection to a power line and an auxiliary phase winding on one of said members, said auxiliary phase winding having a plurality of sections, condenser means having a plurality of sections, a four-arm bridge circuit formed by part of the sections of the auxiliary phase and the condenser means, each of two of the arms of the bridge circuit having at least one section of the auxiliary phase, and the other two arms each having condenser means therein, a switch connected to the cross arms of the bridge, said bridge circuit constituting a part of the auxiliary phase and being connected in series with the remainder of the auxiliary phase and in parallel with the main phase, said switch having a closed circuit and an open circuit position, said switch in one position producing one effect of the turns of the auxiliary phase and a certain effective condenser capacity, and when in the other position decreasing the effect of the turns in the auxiliary phase and the effective condenser capacity. 30
12. A single phase condenser motor of the class described, having two members constituting a stator and a rotor, a main phase winding for connection to a power line and an auxiliary phase winding on one of said members, said auxiliary phase winding having a plurality of sections, condenser means having a plurality of sections, a four-arm bridge circuit formed by part of the sections of the auxiliary phase and the condenser means, each of two of the arms of the bridge circuit having at least one section of the auxiliary phase, and the other two arms each having condenser means therein, a switch having two positions and connected to the cross arms of said bridge for producing one effect of the turns in the auxiliary phase when the switch occupies 35 one position and for reducing the effect of the turns in the auxiliary phase when the switch occupies the other position. 40
